UNITED STATES PATENT OFFICE.

BENJAMIN ROSENBERG, OF NEW YORK, N. Y.

DISPLAY STAND.

1,086,690.

Specification of Letters Patent.

Patented Feb. 10, 1914.

Application filed April 28, 1913. Serial No. 764,068.

To all whom it may concern:

Be it known that I, BENJAMIN ROSENBERG, a citizen of the United States, and a resident of New York, borough of Brooklyn, in the county of Kings and State of New York, have invented certain new and useful Improvements in Display-Stands, of which the following is a specification.

My invention relates to display stands, and the primary object thereof is to produce an improved stand of this description which can be used not only for the exhibition of goods, wares and merchandise, but for advertising purposes as well.

A further object of my invention is to devise an improved display stand which can be easily and cheaply manufactured; given sufficient capacity to adapt it for show windows, stores, shops and other places where articles are intended to be placed for inspection and sale; and yet be so simple in its construction that any one can set it up at an instant's notice.

In its preferred form my display stand is made of a single piece of any suitable material that can be worked into the desired shape. Ordinarily I use pasteboard out of which I form a blank having a central portion and ends bent to extend at an angle therefrom to support the central portion; and out of the central portion I cut a section which is bent back to form a shelf on which the things to be exhibited are put. The shelf is provided with extensions which engage and interlock with the ends, whereby all the parts of the stand are retained in proper relative positions. Advertising matter can be applied to the whole of the front and end surfaces of the stand to indicate not only the character of the articles it carries, but also the name of the maker or seller.

These and other objects and advantages of my invention will more fully appear from the accompanying detailed description, taken in connection with the drawings forming a part of the same; the same reference characters being used on the said drawings to indicate the same parts throughout the different views.

Figure 1 shows in plan view a blank of any suitable material, such as pasteboard; showing how the same is formed and worked to give it the shape required to enable my improved stand to be made therefrom; and Fig. 2 is a perspective view of my stand,

showing the appearance of the same when the blank shown in Fig. 1 is bent to give the parts their proper relative positions and secured to one another.

Describing my invention in detail I take a piece of pasteboard indicated by the numeral 1 and give the same the shape shown on Fig. 1 of the drawings. This blank will be formed to comprise a central or front portion 2 and end members 3; and the central portion 2 and ends 3 will have their adjacent edges bounded by cuts or creases 4 to facilitate bending the blank. The cuts will of course not extend entirely through the board, but only to the required depth into the same, as will be readily understood.

The central section 2 will have its lower edge 5 made straight, to enable the front to rest thereon; but the upper edge 6 will be curved or made other than straight, to give the stand a better appearance. As for the ends 3 they will have their upper and lower edges made convergent; so that when the stand is set up, as shown in Fig. 2, the front will be inclined slightly toward the rear, and the upper edges of the ends will slope downward; thus providing a very neat effect.

In order to exhibit in the most advantageous manner the articles to be exposed on the stand and at the same time efficiently advertise them, I provide a shelf which extends between the ends 3, and I form the front 2 with an opening through which the shelf can be seen. I accomplish this by delineating on the face of the front or central portion 2 a section 9 which is adapted to be cut out, except along one side, which is of course the lower side, and bent back to form the shelf in question. This section 9 will have a transverse or horizontal cut or crease 10, similar to the cuts or creases 4; and the section will be bent along this crease and turned up to form a back 12. Between the back 12 and the front 2 will be the body of the shelf, indicated by the numeral 11. The ends of the shelf will be secured to the ends 3 to hold the ends 3 in position to support the front 2; and the surfaces of the ends 3 and of the front 2 above and below the opening formed by the section 9 when the same is bent back to form the shelf can be covered with any kind of words or designs that may be desired.

For the purpose of efficiently securing the

parts of the stand to one another when my invention is to be set up, I form ears or projections 13 extending laterally from the upper or free corners of the section 9, and 5 I cut vertical slots 14 in the ends 3. The projections 13 pass into these slots, and the projections are formed with notches 15 on their lower edges to give an interlocking engagement of the projections with the 10 slots. The weight of the goods on the shelf 11 will force the projections down far enough to keep the notches 15 and the lower ends of the slots 14 in touch with each other, and thus there will be no likelihood of the 15 end members 3 and the shelf 11 ever getting out of assembled relation.

I form the section 9 by first making a longitudinal cut 16 which is located a certain distance from the edge 6 of the central portion 20 2, referring of course to Fig. 1. This cut extends across the creases 4 into the end members 3. Then I make diagonal cuts at each end of the first cut, these diagonal cuts being shown at 17 and extending a short distance toward the edge 5. I then make cuts 18, parallel to the cut 16, and each extending from an end of one of the cuts 17 across the adjacent crease 4 back into the section 2. From the inner ends of the cuts 18 I make 30 cuts 19 in the front portion 2 extending parallel to the cuts 4, and I join the lower ends of the cuts 19 by means of a crease or cut 20, similar to the crease 10. This completes the section 9 and it can then be bent back along 35 the crease 20 and up along the crease 10, to bring the projections 13 into position to enter the slots 14. I may form the notches 15 after making or cutting out the section 9; or I may form the notches at the same time; 40 thus creating points 25 which may be removed or allowed to remain for ornament if preferred.

The opening formed in the front 2 when the section 9 is bent inward to make the shelf 45 will have the shape illustrated on Fig. 2, and through it the goods of whatever description they may be will be exposed to view. On the remainder of the surface of the front 2 and all of the surface of the end members 2 50 may be put advertising to show character and quality.

In the preferred form of my invention I do not give the crease 20 the same length as the shelf 11. Instead I extend the crease 20 55 only a certain distance from each cut 19. Then I make a pair of short cuts 21 and unite their outer ends by a curved cut 22. Thus I provide a flange 23 which serves to hold the articles carried by the stand in place 60 on the shelf 11, making removal less easy, and minimizing the risk of theft. Similar flanges 24 will be provided by the portions of the front 2, between the cuts 19 and the

creases 4. Creases 26 may be used to enable the projections to be folded in when the ends 65 are bent under the front in shipping.

From this description it will be apparent that I have produced a stand having superior advantages for exhibition and advertising purposes. The manufacture of my stand 70 is easy and cheap; and it can be packed, stored or shipped in knockdown relation. At the same time it is so simple that any one can set it up in an instant; or take it down and put it away when it is no longer to be 75 used.

I of course can utilize any suitable material that can be cut and bent; and while I prefer pasteboard because of the low cost and other advantages thereof I do not limit 80 myself thereto. The blanks of which the stand is made can be cut and printed or otherwise covered with advertising matter to suit the needs of any particular manufacturer or merchant; or if desired they can be 85 delivered with their surfaces free of anything of that nature, leaving the buyer to have them finished for advertising purposes in any manner that he likes.

I wish to have it understood that I can 90 make these stands of any size; and while I prefer to make them in one piece as described I wish to reserve the right to make them in several pieces or parts to be joined together in any suitable way, should occasion require. I also do not wish to be restricted to the exact details of construction herein set forth; but reserve to myself the right to make any changes in the shape, size and arrangement of the several parts that 95 fall within the scope and spirit of my invention.

Having described my invention, what I claim as new and desire to secure and protect by Letters Patent of the United States 105 is:—

In a display stand, the combination of a front and ends to support the front, the said ends having vertical slots therein, the said front having a portion extending rearward 110 to form a shelf, the shelf having a section extending upward to form a back, the back carrying projections in the plane thereof and being in line with the slots, whereby the projections will hold the shelf and the ends in 115 proper position, and the weight of the shelf and its contents exerted edgewise against the projections.

Signed at New York in the county of New York and State of New York this 21st day 120 of April A. D. 1913.

BENJAMIN ROSENBERG.
